UNITED STATES PATENT OFFICE.

HUBERT R. HUMPHREY, OF KALAMAZOO, MICHIGAN.

GAS BURNER.

1,425,097.

Specification of Letters Patent. Patented Aug. 8, 1922.

Application filed May 13, 1921. Serial No. 469,138.

To all whom it may concern:

Be it known that I, HUBERT R. HUMPHREY, a citizen of the United States, residing at the city of Kalamazoo, county of Kalamazoo, 5 State of Michigan, have invented certain new and useful Improvements in Gas Burners, of which the following is a specification.

This invention relates to improvements in gas burners.

10 My improved gas burner is especially designed by me for use in gas heaters, and I have illustrated one type of heater on which I have used the same in my application for Letters Patent Serial #339,917, 15 filed Nov. 22, 1919, one form of my burner improvements as illustrated in this application being illustrated in such application.

The main objects of this invention are:—

First. To provide an improved burner 20 having a plurality of aligned burner tips in which the gas is quite uniformly delivered to the several tips.

Second. To provide an improved gas burner of the multiple tip type having the 25 above advantage, which is simple and economical in structure and not likely to get out of repair in use.

Further objects, and objects relating to structural details, will definitely appear 30 from the detailed description to follow.

I accomplish the objects of my invention by the devices and means described in the following specification. The invention is clearly defined and pointed out in the claims.

35 A structure which is a preferred embodiment of my invention is clearly illustrated in the accompanying drawings, forming a part of this application, in which:

Fig. I is a front perspective view of a gas 40 heater embodying the features of my invention, a portion only of the radiants being illustrated.

Fig. II is a detail vertical section on a line corresponding to line 2—2 of Fig. I.

45 Fig. III is a fragmentary view partially in longitudinal section through the burner on a line corresponding to line 3—3 of Fig. II.

Fig. IV is a fragmentary sectional view 50 corresponding to that of Fig. III of a

slightly modified form or embodiment of my invention.

Fig. V is a fragmentary section corresponding to that of Figs. III and IV of another modified form or embodiment of my 55 invention, the section being on line 5—5 of Fig. VI.

Fig. VI is a transverse detail section on a line corresponding to line 6—6 of Fig. V.

In the drawings similar reference characters refer to similar parts throughout the several views, and the sectional views are taken looking in the direction of the little arrows at the ends of the section lines.

Referring to the drawings, the base 1 is 60 provided with an upwardly projecting arm or standard 2 carrying a pivot 3 for the arm 4 of the heater body 5. Within this heater body is a fireback 6, in front of which are arranged the radiants 7, the heater body 70 being provided with openings 8 with which the radiants are aligned to receive the tips of my improved gas burner.

My improved gas burner, the body of 75 which is designated generally by the numeral 9, is provided with a cylindrical manifold chamber 10 and internal annular rib-like partition members 11. These ribs are preferably irregularly spaced, the purpose of which will appear as the description proceeds. Fitting within these ribs is a tubular screen 12 forming with the ribs a plurality of annular discharge compartments 13 opening through the screen into the manifold chamber. The burner tips 14 open into 80 these compartments or open between the ribs. A Bunsen tube 15 projects into the manifold chamber and preferably discharges adjacent the outer end thereof, as shown in Fig. III. A yoke-like bracket 16 is provided 90 for supporting the nozzle 17 in alignment with the Bunsen tube. 18 represents a nipple to receive the gas supply connection.

The burner is provided with the opening 19 at its outer end through which the screen 95 may be introduced and removed, the closure 20 for this opening also serving as a support for this screen.

By this arrangement of parts the gas is quite uniformly delivered to the several 100

burner tips and one tip does not "rob" the adjacent tips. The ribs are preferably irregularly placed, those at the outer end being disposed to make smaller discharge chambers than those at the inner end, as the pressure of gas is greatest at the discharge end of the Bunsen tube. However, very satisfactory results are secured where the ribs are uniformly spaced, as the tendency of one tip to "rob" another is quite effectively overcome.

In the modification shown in Fig. IV the partition members 21 serving the purpose of the ribs 11 are in the form of rings and 15 may be either fitted within the manifold chamber to receive the screen or fitted on the screen and then slipped into the chamber.

In the modification shown in Figs. V and 20 VI the body 22 of the burner is semi-circular in cross section, having a movable top plate 23 with partition members 24 thereon coacting with the flat screen 25 in providing a series of discharge compartments 13.

25 My improved burner is very efficient and as stated, the tips are very uniformly supplied with gas, and the parts are simple and economical to produce and not likely to get out of repair in use.

30 Having thus described my invention, what I claim as new and desire to secure by Letters Patent, is:—

1. In a gas burner, the combination of a 35 body member provided with a cylindrical manifold chamber and internal annular ribs irregularly spaced therein, a tubular screen arranged in said manifold chamber and coacting with said ribs to provide a plurality of annular delivery chambers of different capacities, burner tips mounted on said body member opening into said delivery chambers, the outer end of said body member being open to receive said screen, a closure for said opening on which the outer end 40 of said screen is mounted, and a Bunsen tube projecting into said manifold centrally of said screen and discharging adjacent the outer end thereof.

2. In a gas burner, the combination of a 50 body member provided with a cylindrical manifold chamber and internal annular ribs irregularly spaced therein, a tubular screen arranged in said manifold chamber and coacting with said ribs to provide a plurality of annular delivery chambers of different capacities, burner tips mounted on said body member opening into said delivery chambers, and a Bunsen tube projecting into said manifold centrally of said screen and discharging adjacent the outer end thereof.

60 3. In a gas burner, the combination of a body member provided with a cylindrical manifold chamber and internal annular ribs spaced therein, a tubular screen arranged 65 in said manifold chamber and coacting with

said ribs to provide a plurality of annular delivery chambers, burner tips mounted on said body member opening into said delivery chambers, the outer end of said body member being open to receive said screen, 70 a closure for said opening on which the outer end of said screen is mounted, and a Bunsen tube projecting into said manifold centrally of said screen.

4. In a gas burner, the combination of a 75 body member provided with a cylindrical manifold chamber and internal annular ribs spaced therein, a tubular screen arranged in said manifold chamber to coact with said ribs to provide a plurality of annular delivery chambers, burner tips mounted on said body member opening into said delivery chambers, and a Bunsen tube projecting into said manifold centrally of said screen.

80 5. In a gas burner, the combination of a body member provided with a cylindrical manifold chamber, a cylindrical screen arranged in said manifold chamber, annular partition members associated with said 85 screen, providing a plurality of discharge compartments of different capacities, burner tips opening into said compartments, and a Bunsen tube projecting into said manifold chamber and discharging adjacent the rear 90 end thereof.

95 6. In a gas burner, the combination of a body member provided with a cylindrical manifold chamber, a cylindrical screen arranged in said manifold chamber, annular 100 partition members associated with said screen, providing a plurality of discharge compartments, burner tips opening into said compartments, and a Bunsen tube projecting into said manifold chamber.

105 7. In a gas burner, the combination of a body member having a manifold chamber therein, a screen extending across said chamber, partition members associated with said screen providing a plurality of discharge 110 compartments of different capacities, and a Bunsen tube projecting into said manifold chamber and discharging adjacent the rear end thereof.

115 8. In a gas burner, the combination of a body member having a manifold chamber therein, a screen extending across said chamber, partition members associated with said screen providing a plurality of discharge 120 compartments of different capacities, and a Bunsen tube projecting into said manifold chamber, the capacity of the chambers increasing as their distance from the point of delivery of the Bunsen tube increases.

125 9. In a gas burner, the combination of a body member having a manifold chamber therein, a screen extending across said chamber, partition members associated with said screen providing a plurality of discharge compartments, tips mounted on said burner 130

body and opening one to each compartment and a Bunsen tube projecting into said manifold chamber and discharging adjacent to the rear end thereof, said Bunsen tube being arranged so that there is an unobstructed passage for the gas from the discharge thereof to each of the said chambers.

In witness whereof, I have hereunto set my hand and seal in the presence of two witnesses.

HUBERT R. HUMPHREY. [L. S.]
